CLAIM

The ornamental design for an electrode, as shown and described.

DESCRIPTION

FIG. 1 is a front perspective view of an electrode according to the present invention.

FIG. 2 is an enlarged front view of the electrode of FIG. 1.

FIG. 3 is an enlarged rear view of the electrode of FIG. 1.

FIG. 4 is a left side view of the electrode of FIG. 1.

FIG. 5 is a right side view of the electrode of FIG. 1.

FIG. 6 is a top view of the electrode of FIG. 1; and,

FIG. 7 is a bottom view of the electrode of FIG. 1.

The dashed lines illustrate environment that does not form a part of the present invention, and no claim is made to the material illustrated with dashed lines.

1 Claim, 6 Drawing Sheets
